DESIGN FOR A COVER FOR A SUTURE JAR

Robert L. Eddy, Warsaw, N. Y.

Application September 8, 1945, Serial No. 121,947

Term of patent 7 years

(Cl. D58—26)

To all whom it may concern:

Be it known that I, Robert L. Eddy, a citizen of the United States, residing at Warsaw, in the county of Wyoming and State of New York, have invented a new, original, and ornamental Design for a Cover for a Suture Jar, of which the following is a specification, reference being had to the accompanying drawing, forming a part thereof.

Figure 1 is a side elevation of the cover for a

suture jar embodying my design. Figure 2 is a top plan view of the same. Figure 3 is a bottom plan view thereof. Figure 4 is a cross section thereof taken on line 4—4, Figure 1.

I claim:

The ornamental design for a cover for a suture jar, substantially as shown.

ROBERT L. EDDY.
